UNITED STATES PATENT OFFICE

2,480,515

DISPLAY RACK

Clyde V. Smith, Los Angeles, Calif.

Application November 20, 1945, Serial No. 629,819

4 Claims. (Cl. 211—100)

1

My present invention relates to display racks intended to hold articles of apparel and it has for its object to provide one comprising an arm which is adjustable from an out of the way position into a horizontal position in which it is supported for rotary movement in a horizontal plane to better display articles mounted thereon, and may be readily returned to the first mentioned position.

My invention also comprehends an arrangement of parts adapted to be made entirely of wood comprising a base or bracket member adapted for mounting on a wall or other support and a goods carrying arm pivoted thereon for movement in two directions; one from the vertical to the horizontal; the other for rotary adjustment when in the horizontal position.

Another object of my invention is to provide an arm for supporting apparel pivoted on a supporting member and laterally movable on its pivot for otherwise cooperating with the base to hold it horizontally for better displaying the articles carried thereon.

To these and other ends my invention embodies further improvements all as will be fully set forth in the accompanying specification, the novel features thereof being set forth in the appended claims.

In the drawings:

Figure 1 is a side view of a display rack illustrating one embodiment of my invention showing the apparel supporting arm in its extended position.

Figure 2 is a top plan view thereof.

Figure 3 is a front face view or elevation of the parts shown in Figure 1.

Figure 4 is a side elevation partly in section of another way in which the base and rack arm may be constructed to provide by their relative movement the pivotal connections accommodating the adjustment of the arm in a vertical plane and also for rotating it in its elevated position.

Figure 5 is a top plan view of the parts as arranged in Figure 4.

In the drawings similar reference numerals indicate similar parts.

Economizing of space under the circumstances affecting present day living conditions is important and to this end I have provided a folding rack designed more particularly for supporting articles which can be folded and suspended in an out of the way position against a wall, a closet door, or similar support, when not in use, and which may be projected into full view for ready access by adjustment of the rack into a horizontal or projected position. To this end I have de-

signed a structure comprising few parts which may be constructed cheaply and easily assembled.

In carrying out my invention I make a base member or support of wood in the nature of a bracket having a vertical portion 1 and a horizontal shelf 2, the part 1 being adapted to be secured to the wall of a room or closet, as by screws 3, and the part 2 being tapered on its side edges, as shown in Fig. 3, and provided with a central aperture 19.

Fitted in said aperture is a pin 5d which is slotted transversely but is notched crosswise, as indicated at 5e, forming hooks with which the ends of a cross pin 6d, carried on the rack arm 17d may be engaged. The rear end of the arm 17d extends beyond pin 6d and is embraced between links 13 to which it is pivoted by a pin 14. The upper ends of these links are also pivoted on a journal 15 extending across the slot in pin 5d, the relative position of these parts being such that when the pin 6d is disengaged from the notches 5e the rack arm will be suspended in a vertical plane in alignment with the pin 5d. Cross pieces 100 or other means for holding goods may extend laterally from opposite sides of arms 17d and it will readily be seen that when the arm is extended horizontally it may be shifted from one side to the other by the rotary movement permitted by pin 5d.

Another manner in which my invention may be carried out will be seen from an inspection of Figures 4 and 5. The bracket used here is of angular formation similar to that of Figs. 1, 2 and 3 but the aperture in the shelf portion 2c has the corners rounded, those at the top being on a longer radius than those at the bottom, and the periphery of the shelf is semi-circular. The inner end of the rack arm 17c is given a goose neck 20 which extends over the ring 21 formed on the shelf 2c. This neck portion is extended sufficiently to provide for a limited longitudinal movement of the arm, the same as is accomplished by the links 13 of Figs. 1 and 3. Its shape provides spaced stops 20a, 20b which alternately engage the opposite sides of the ring formed on the bracket shelf. Below the stop 20a on the underside of said goose neck is a projection 20c which, when the rack arm is pulled forwardly, extends beneath the forward portion of the bracket ring 21. Also extending rearwardly on the end of said neck in alignment with projection 20c is another projection 20d which is adapted to have a hooking engagement with the underside of the bracket shelf 2c. The bottom edge of the web between the extremities of these two projec-

tions is curved and the distances between them is such that they easily pass through the bracket ring when the rack arm is moved from its inoperative vertical position, as shown in dotted lines, to the horizontal display position shown in full lines in Fig. 4. If desired a retractile spring 9b may be connected between a point on the lower side of the rack arm and the bracket in which location it operates to restrain the arm in both of its adjustments.

Each of the different structures illustrated embody common characteristics in that a rack arm is provided which when moved from the inoperative vertical position to the operative or horizontal position is capable of being locked in the latter position by a slight rearward movement on its supporting bracket and released by drawing it forwardly. It will also be observed that in each of the forms illustrated provision has been made whereby when the rack arm is in its operative or extended position it may be rotated on its support to afford access first to one side thereof and then to the other.

I claim:

1. A display rack comprising a bracket for attachment to a wall having an outwardly extending horizontal shelf, a vertical pin journaled in an aperture therein having a slotted lower end projecting below the shelf and provided with a notch, a pivoted link carried by the pin, a rack arm pivotally mounted on the link and a stud on the arm engageable in said notch to hold the arm in extended display position. 25

2. A display rack comprising a bracket for attachment to a wall having an outwardly extending horizontal shelf, a vertical pin journaled in an aperture therein having a slotted lower end projecting below the shelf provided with a notch in its forward edge, a link pivoted in said slot above the notch, a rack arm pivotally supported from the lower end of the link in a vertical position in alignment with said pin and movable 30

thereon into an elevated display position, a stud on the arm engageable with said notch to support the arm in the last mentioned position.

3. A display rack comprising a horizontal bracket for attachment to a wall, a notched vertical pin journaled therein having a lower slotted end projecting below the bracket, a link pivoted on the pin, a goods display arm pivoted on the link and having a stud thereon engageable in the pin notch, said arm having an end entering the slot in the pin and cooperating with said pin by its movement on the link to alternately suspend it in a vertical position or hold it in an elevated position. 10

4. A display rack comprising a horizontal bracket for attachment to a wall, a notched vertical pin journaled therein having a lower slotted end projecting below the bracket, a link pivoted on the pin, a goods display arm pivoted on the link in a suspended vertical position below the pin and having a stud thereon cooperating with the pin notch upon relative movement of the link to said pin to support the arm in an elevated position. 15
